Attorney, Agent, or Firm—Quarles & Brady

[57] **CLAIM**

The ornamental design for a faucet, as shown and described.

DESCRIPTION

FIG. 1 is a perspective view taken from the top, front and left side of a faucet embodying my new design;

FIG. 2 is a top plan view thereof;

FIG. 3 is a right side elevational view thereof, the left side being a mirror image of the right side;

FIG. 4 is a bottom plan view thereof;

FIG. 5 is a rear elevational view thereof;

FIG. 6 is a front elevational view thereof;

FIG. 7 is a perspective view taken from the top, front and left side of a second embodiment of my new design;

FIG. 8 is a top plan view of FIG. 7;

FIG. 9 is a right side elevational view of FIG. 7, the left side being the mirror image of the right side;

FIG. 10 is a bottom plan view of FIG. 7;

FIG. 11 is a rear elevational view of FIG. 7; and,

FIG. 12 is a front elevational view of FIG. 7.

FIG. 1

FIG. 2
